COMPOUND STEAM LOCOMOTIVE

Georges Baillot, deceased, late of Embourg, near Liege, Belgium, by Helene Baillot, Liege, and Germaine Baillot, Embourg, near Liege, Belgium, sole heirs, and Ernest Baillot, Liege, Belgium

Application May 25, 1950, Serial No. 164,132
In Belgium June 4, 1949

3 Claims. (Cl. 121—102)

1

The invention relates to compound locomotives and the object in view is to realize in a steam locomotive of this type a double integral expansion, which will permit the power of the locomotive to be increased.

In the compound system, it is well known that the anticipated high pressure exhaust causes at the receiver a pressure drop without work, which is a loss all the larger as this exhaust generally takes place in full low pressure admission. The ideal solution would be, after getting the complete high pressure expansion, to obtain a perfect pressure balance between the returning surfaces of the small pistons and the receiver, so that any pressure drop at receiver would only concur with the admission or better with the low pressure admission lead. But this would entail a large loss of work because of the excess compression in the high pressure cylinders and would involve serious operating difficulties, especially at high speeds.

This compression excess arises from the fact that the steam on the returning surface of high pressure pistons can no longer be delivered to the receiver on account of the progressive narrowing of the passage at exhaust ports, and is already compressed at the exact moment of port closing, causing thus a real pre-compression.

Attempts have been made to obviate this trouble by giving a more or less negative value to the outside laps of high pressure slide valves and by artificially increasing the clearances at admission cylinders, but this could only be obtained at the cost of many constructional complications.

This invention affords a very simple solution of this problem by realizing a double integral expansion locomotive, in which in each set comprising one high pressure and one low pressure cylinder, the corresponding cylindrical distributing valves are exactly contiguous and comprise each three separate chests, the central one being kept, in the small slide valve, for the working steam admission, and in the large slide valve for the concentration of the two exhausts to the chimney, while the two end chests, connected on either side from one slide valve to the other, receive the primary expansion exhaust steam.

Thus, as the two end chests are in one piece in the two slide valves, two small receivers, independent from each other, are obtained in each set of two cylinders.

It can be understood that the rush of the non-condensing exhaust of the large slide valve or

2

of low pressure cannot lead to the slightest reaction on the steam valve gear and, as there is a recess in the slide valves, a perfectly balanced pressure will be set up at the ends of the steam chests, where the use of a steam trap is certainly advisable. At the same time, this pressure of steam containing oil and condensation water is a further security for the slide valve tightness and also provides ample lubrication to the rods and packing.

The accompanying drawings forming a part of this specification show by way of example an embodiment of the invention.

Fig. 1 shows schematically a front half view and half section of an improved compound locomotive, in which the low pressure cylinders are set inside the frame and the high pressure cylinders outside on either side;

Fig. 2 is a partial view partly in section in a high pressure cylinder and its distributing valve on the line II—II of Fig. 1;

Fig. 3 is a section on the line III—III of Fig. 1, in the block formed by the two slide valves of a high pressure and low pressure cylinder set, the high pressure cylinder being shown in partial section.

Referring to the drawings, a valve gear 3 is coupled with high pressure cylinder 1 and low pressure cylinder 2 and comprises one high pressure slide valve 4 and one low pressure slide valve 5, cast integrally or otherwise. These two slide valves are each driven by a Walschaert gear and, were it not for the advantage obtained by the increase of the low pressure admission against the high pressure admission, the two slide valves could be coupled and driven by a common link.

Each slide valve 4 and 5 has four rings 6 provided with packings to ensure tightness and they move respectively inside the cylindrical faces 7 and 8 separated from each other in valve gear 3 by a partition 9 which is drilled with side passages 10. In each valve 4 and 5, the rings 6 delimit three distinct chests A, B, C and A', B', C'. The middle chest B of slide valve 4 is intended for the inlet of working steam through the intake port 14, while the middle chest B' of slide valve 5 is intended for collecting the low pressure exhaust steam to the chimney. These two chests B and B' are quite distinct, and they are separated by the partition 9. The cylindrical face 7 is drilled with ports 11 and 11' corresponding to passageways 12 and 12' of the high pressure cylinder, while the cylindrical face

55 8 is drilled with ports 13 and 13' corresponding

to identical passageways (not shown) of the low pressure cylinder 2.

Moreover, the cylindrical face 7 is drilled with ports 15 and 15' and cylindrical face 8 with ports 16 and 16', which ensure connection through side passage 10 between chests A and A' and C and C'; these chests alternately receive exhaust steam from the high pressure cylinder or primary expansion i. e. the admission steam to the low pressure cylinder. These end chests thus really form by their dual connection two small intermediate and independent tanks or receivers. According to this invention, the slide valves coupled to the cylinders will thus form in a four-cylinder locomotive four small receivers A—A', C—C' independent from each other, the regulating function of which allows in optimum conditions, the development of the different distribution phases, as well for high as for low pressure. Thus, the compartments A—A' and C—C' form two small independent intermediate receivers. Since the locomotive has two high pressure cylinders and two low pressure cylinders (as seen in Fig. 1) there are in all four small independent receivers.

Since there is no connection in each two-cylinder set between the receivers, it has been possible to give high negative values to the high pressure exhaust laps, without any fear of establishing connection through the ports between the two surfaces of the small piston for the middle position of their slide valves. It results therefrom that the steam which has been working on the front surface of a small piston can only expand on the front surface of the corresponding large piston, and the same happens for the back surfaces of the pistons in question.

The boiler working steam admitted for instance on the front surface of a small piston expands slightly therein by a 5 mm. stroke of the slide valve, and then unites, due to a greatly anticipated exhaust, with the steam volume contained in its intermediate space and which is brought at about two thirds of the boiler pressure. The high pressure expansion then continues up to full stroke having been supported by the steam of the small receiver and acting here as a feeder, so that at the return piston stroke, the pressure balance of the whole of the intermediate steam volume is more than ensured. The pressure drop of this volume will then concur with admission or better with low pressure admission lead, to obtain the proper expansion and with the other well-known phases of the locomotive distribution.

In the present device, the pressure stored each time in the intermediate spaces has been estimated to be $\frac{2}{3}$ of the boiler pressure. By careful use of the low pressure admission, this pressure can be brought to the most advantageous point, in order to prevent the slightest pressure drop when the contents of one receiver is added to the intermediate steam volume. This addition, and consequently the intermediate balance, will in fact always be attained even when the piston has not travelled half of its stroke.

The steam chests and slide valves are combined in such a way that a steam passage section of at least 3 dm.² (46.5 square inches) between high and low pressure ports is provided at each receiver or intermediate space, for each position of the distributing valve, and, as the largest admission, increased by 40%, is still ensured between the returning surface of the small piston and the expansion cylinder, no risk of the least detri-

mental resistance or pre-compression at high speeds is to be feared.

From the foregoing, it can be inferred that the double integral expansion as outlined above can increase the power of the locomotive by 28 to 30%.

The system used for the starting of the four-cylinder compound locomotives is well known: it consists in releasing the exhausts of all cylinders to the atmosphere. This result can only be achieved after very expensive engineering complications. In the present instance, compression-release valves are used, such as 17, set on the low pressure cylinder bottom ends, which should be properly regulated (Fig. 2).

Each high pressure cylinder is provided with two small working steam feed cocks 18. These cocks are set in such a manner that their ports will be hidden by the high pressure cylinder pistons which act here as valve gears whenever these pistons arrive at the $\frac{3}{4}$ stroke point in each direction (Fig. 2). This precaution is necessary in order to offer some security against an eventual compression of high pressure when the moment of maximum use, i. e. $\frac{1}{2}$ of admission, is exceeded. This admission, as long as it lasts, has in fact the function of limiting to 8 kgs. (17.5 lbs.) in the present instance the back-pressure by means of the valves situated on the low pressure cylinder bottom ends. It should be noted that the locomotive power in its more disadvantageous position will be by far—up to 25%—larger than the power developed by the exhaust system of four-cylinder compound locomotives.

Having now particularly described and ascertained the nature of the said invention, what is claimed is:

1. In a compound steam locomotive, two cylinder groups, each comprising a high pressure cylinder and a low pressure cylinder, each group of cylinders being served by cylindrical distributing valves forming a block, said distributing valves defining three distinct compartments, a partition uniting the two distributing valves, said partition having two lateral end passages and two distinct central compartments, forming with the compartments provided in said distributing valves a central chamber for admitting steam into the high pressure cylinder, a central chamber for the outlet of steam from the low pressure cylinder, and two distinct lateral chambers defining independent receivers for the passage of the steam from the high pressure cylinder to the low pressure cylinder.

2. In a compound steam locomotive, two cylinder groups, each comprising a high pressure cylinder and a low pressure cylinder, each group of cylinders being served by cylindrical distributing valves forming a block, said distributing valves defining three distinct compartments, a partition uniting the two distributing valves, said partition having two lateral end passages and two distinct central compartments, forming with the compartments provided in said distributing valves a central chamber for admitting steam into the high pressure cylinder, a central chamber for the outlet of steam from the low pressure cylinder, and two distinct lateral chambers defining independent receivers for the passage of the steam from the high pressure cylinder to the low pressure cylinder, communication being prevented between the two faces of the high pressure pistons in the central position of the corresponding valve.

3. In a compound steam locomotive, two cylinder groups, each comprising a high pressure cylinder and a low pressure cylinder, each group of cylinders being served by cylindrical distributing valves forming a block, said distributing valves defining three distinct compartments, a partition uniting the two distributing valves, said partition having two lateral end passages and two distinct central compartments, forming with the compartments provided in said distributing 10 valves a central chamber for admitting steam into the high pressure cylinder, a central chamber for the outlet of steam from the low pressure cylinder, and two distinct lateral chambers defining independent receivers for the passage of 15 the steam from the high pressure cylinder to the low pressure cylinder, decompression valves mounted on the low pressure cylinders to facilitate starting, and the high pressure valves being

provided with a distributor defined by two live steam feed cocks, the openings of said cocks being masked by the corresponding pistons each time the latter reach about 7.5 tenths of their stroke in both directions.
